ABSTRACT OF THE DISCLOSURE

Pneumatic takedown apparatus for a hosiery knitting machine is described as having an elbowed, but stationary, takedown tube that feeds a horizontally disposed tube which is rotated with the needle cylinder. Elbowing the takedown tube permits of a knitting machine with a shortened overall height; and rotating the horizontal feed tube prevents stockings which are knit by the machine from being twisted into knots in the elbow of the takedown tube.

BACKGROUND OF THE INVENTION

Field of the invention

The invention relates to pneumatic takedown apparatus for a ladies hosiery knitting machine, being concerned principally with the prevention therein of twisting of stockings into knots prior to their being cast off by the needles of such machine.

Description of the prior art

Pneumatic suction takedowns are well known in the art for tensioning a stocking for even drawing of stitches therein. Such takedowns usually embody a hollow tube through which a vacuum is applied to the stocking, and through which the stocking passes, after it is cast off, for further processing. The vertical length of the takedown tube has heretofore been at least as long as the stocking being knit, thereby effecting an overall machine height which is greater than would otherwise be desired. Hosiery knitting machines are usually recessed below floor level to permit eye level inspection of their knitting instrumentalities by maintenance men and mechanics. This obviously is undesirable, not only because it creates a general problem with respect to the housing of hosiery knitting machines, but further because such lengthy takedown tubes are intrinsically unsightly and lend an otherwise gangling appearance to what is already a complicated appearing machine.

SUMMARY OF THE INVENTION

To obviate the need for a takedown tube that is vertically at least as lengthy as a stocking, the present invention suggests a takedown tube that is bent so that its vertical length is less than stocking length. The bent end is disposed generally horizontally and has vacuum applied to it via a sleeve that couples to the bent end, such sleeve being however rotatable about the horizontal axis of the bent end of the takedown tube. Rotation of the sleeve is generally at about the speed of cylinder rotation, i.e., at the speed of stocking rotation, and it is this feature which permits of a practical shortened machine. While the stocking is knit and drawn down into the elbow of the takedown tube, the end of the stocking which first reaches the elbow tends to remain stationary therein and, as the trailing end of the stocking is carried around in the vertical portion of the takedown tube during knitting thereof, the stocking tends to twist and clog up at the elbow portion of the takedown tube. The rotating sleeve sucks the leading end of the stocking into it, and since it rotates with the needle cylinder, it carries the leading end of the stocking

2

with it, thereby unwinding the stocking and eliminating any tendency of the stocking to twist.

A principal object of the invention is to provide improved takedown apparatus for a hosiery machine.

Another object of the invention is to provide a hosiery machine, the takedown of which is vertically shorter than stocking length.

The invention will be described with reference to the figures wherein

FIG. 1 is a perspective view, partially broken away, showing in elevation a hosiery knitting machine embodying takedown apparatus according to the invention,

FIG. 2 is a perspective view showing the details of construction of the takedown apparatus embodied by the machine of FIG. 1, and

FIG. 3 is a side sectional view of the sleeve portion of the takedown apparatus of the invention.

Referring to the figures, a hosiery knitting machine 10 includes a yarn stand 12 the yarns of which are fed to the needles of a needle cylinder 14 shown generally in phantom. The needle cylinder 14 mounts a bed plate 16, and the knitting instrumentalities of the machine are under control of a main control drum 18, as is conventional practice. The control drum 18, which is itself controlled by means of a timing chain 20, is hollow and rotatably mounts atop a support plate 22 coaxially with the needle cylinder 14. The support plate 22 sits on legs 23, and the bed plate 16 is held above the support plate 22 by means of posts 25. The control drum 18 is adapted to have stockings which are knitted by the needle cylinder 14 pass through it to takedown apparatus indicated generally at 24.

The takedown apparatus 24 includes a hollow takedown tube having a vertical portion 26 about which the needle cylinder 14 and control drum 18 are individually rotatable, and through which a stocking 28 is adapted to pass in conventional manner. Coupled to the vertical portion 26 in generally airtight fashion, by means of a collar 30, is the remaining portion of the takedown tube, namely hollow elbow piece 32, the vertical dimension *d* of the vertical portion 26 and elbow 32 being less than the overall length of the stocking 28. A hollow sleeve 34 provided with a flange portion 36, back a bit from its end 38, has such end fitted for rotation within the horizontal portion 40 of the elbow 32, the flange 36 serving as a shoulder for the end 40 of the elbow 32. A collar 42 frictionally secures to the elbow 32, and then secures by means of bolts 44 both to a brace 46, supported by the machine 10, and to a bearing 48. Preferably the end 38 of the sleeve 34 is fitted with a sponge-like annular piece 49 that serves to prevent snagging of the stocking 28 by the edge of the sleeve 34.

The other end of the sleeve 34 is provided with a flange portion 50 which is coupled in generally airtight manner to a stationary suction piece 52 for rotation relative thereto. The suction piece 52, which has a collar 54 frictionally secured thereto, secures both to a bearing 56 and to the brace 46 by means of bolts 58. A third collar 60, this being positionably axially secured to the sleeve 34 by means of bolts 62 which ride in slots 64, mounts a drive wheel 66 by means of screws 68. The drive wheel 66 is provided with a frictional periphery 70 adapted to contact a drive disc 72. The drive disc 72 is provided with a frictional face 74 so that rotation of the disc 72 will rotate the wheel 66 to rotate, in turn, the sleeve 34 in its bearings 48 and 56. The drive disc 72 is supported on a shaft 76 having a fixedly positioned collar 78 that serves to restrain a spring 80 so that the spring 80 loads the drive disc 72 against the frictional periphery 70 of the drive wheel 66, the disc 72 being positionable in the direction of the axis of the shaft 76 by means of a key 82 that rides in a slot 84 in a collar 86 on the disc 72. The drive shaft 76 mounts for rotation in bearings on the support plate 22,

being driven by a belt 90 by means of the same drive 92 that operates the needle cylinder 14. Therefore, speed changes in the needle cylinder are immediately followed upon by corresponding speed changes in the shaft 76 and its related components, viz. the sleeve 34. By positioning the collar 60 and the drive wheel 66 axially of the sleeve 34, i.e. radially of the drive disc 72, the speed of rotation for the sleeve 34 may be adjusted as desired. It has been found preferable to position the drive wheel 66 for rotation of the sleeve 34 at just slightly greater speed than the needle cylinder speed, whereby slippage of the stocking within the sleeve 34 is compensated for. The suction piece 52 couples in airtight fashion to a suction system 96 of conventional design, which system is fed by means of a hose 98. With the needle cylinder 14 and stocking 28 rotating as indicated by corresponding directional arrows, the trailing end of the stocking 28, will tend to twist clockwise (looking down upon the needle cylinder 14) with respect to the leading edge, of the stocking, i.e., its welt, once such leading edge reaches, and sits within, the elbow 32. By rotating the sleeve 34 as indicated by its corresponding arrow, while sucking the stocking welt portion into the sleeve 34, both the leading and trailing stocking ends are simultaneously rotated in the same direction, and attendant twisting thereof is precluded.

While the invention has been described in its preferred form it is to be understood that the words which have been used are words of description rather than of limitation, and changes within the purview of the appended claims may be made without departing from the true scope and spirit of the invention.

Having thus set forth the nature of this invention, what is claimed herein is:

1. In a hosiery knitting machine (10) with pneumatic takedown apparatus (24) having a stationary takedown tube (26, 32) which includes a stationary vertical portion (26) having a longitudinally axis coincident with the axis of rotation of the needle cylinder of the machine and which also includes a stationary elbow (32) having one end connected to the lower end of said vertical portion (26), the improvement

(a) wherein said takedown apparatus (24) includes a

sleeve (34) which is mounted for rotation about its longitudinal axis on the other end (40) of the elbow (32), and to which suction may be applied to draw a stocking through the takedown tube (26, 32) and sleeve (34), and

(b) wherein said takedown apparatus (24) includes means (66) for rotating said sleeve (34) about its longitudinal axis to eliminate twist in stockings being made longer than the vertical height (d) of the take-down tube (26, 32).

2. The apparatus of claim 1 including means (92, 90, 76, 72) drivingly coupling said sleeve (34) to said needle cylinder (14), whereby said sleeve (34) may be rotated about its axis coincidentally with rotation of said needle cylinder (14).

3. The apparatus of claim 2 wherein said means (92, 90, 76, 72) drivingly coupling said sleeve (34) and needle cylinder (14) includes means (60, 62) for adjusting the speed at which said sleeve (34) may be rotated.

4. The apparatus of claim 2 wherein said means (92, 90, 76, 72) drivingly coupling said sleeve (34) and needle cylinder (14) is adapted to rotate said sleeve (34) about its axis at a speed slightly in excess of the speed at which said needle cylinder (14) is rotated about its axis.

5. The apparatus of claim 2 wherein said sleeve (34) and the said other end (40) of said elbow (32) have coincidental longitudinal axes which are both horizontally disposed.
